FLUID OPERATED CONTROL SYSTEM

Cecil E. Webb, Norwood, Ohio, assignor to M. S. Bowne, Clearfield, Ky., as trustee

Application June 23, 1949, Serial No. 100,943

5 Claims. (Cl. 121—41)

1

This invention relates to servo-motor apparatus for controlling steam extrusion presses and other equipment having pressure operated pistons requiring accurate stroke regulation by a hand operated control valve or throttle. As applied to a steam press, the apparatus constitutes a relay or auxiliary power system interposed between the main steam control valve and hand lever or other control device, the control apparatus being arranged to operate the main valve by fluid pressure in response to movements of the hand lever and thus to regulate piston movements accurately but with very little manual effort.

Steam operated presses have been in use for a great many years for extruding plastic clay tubes which are made into tile drainage and sewer pipes. Such presses essentially consist of a steam cylinder having a piston connected to an extruder ram, the movements of the piston being controlled by a reversible steam valve arranged to admit steam into one end of the cylinder to drive the piston forwardly during the extrusion stroke and to admit steam into the opposite end of the cylinder to retract the piston at completion of the stroke. In retracted position, the ram is withdrawn from its chamber to provide an opening for charging plastic clay into the chamber for the next operation.

The general practice has been to operate the main steam valve by a hand lever connected directly to the steam valve plunger in such a way that by manipulating the handle the piston can be moved in either direction and the valve throttled to control rate of piston movement. These machines are quite massive and the control valve offers considerable resistance to movement because of steam pressure and friction between moving parts. The valve must be operated almost continuously while the machine is in operation to control extrusion speed and to stop the piston as each tube length is extruded. Because of resistance, it is difficult for the operator to throttle the valve accurately, hence the extrusion process oftentimes is not controlled as precisely as it should be for best results. Since the pressure required to move the lever is in the neighborhood of 60 pounds on large machines, it will be appreciated that operation of such a press is very fatiguing to the operator.

To prevent the piston from retracting beyond a fixed limit and striking the top cylinder head with possible damage, it has been customary to provide a safety device operable to move the hand lever automatically to valve closing position when the limit of travel is reached. This causes the

hand lever to be kicked rather violently to neutral or valve closing position and is dangerous to the operator.

5 The present apparatus was designed primarily to reduce the effort of controlling the steam valve and to protect the operator from injury and for this reason the structure is disclosed in conjunction with a steam extrusion press, although it is contemplated to apply the apparatus to other machinery having pistons or rams powered by fluid pressure other than steam.

10 The primary objects of the invention have been to provide a simplified fluid operated control apparatus which may be applied readily to conventional hand controlled presses to render valve operation almost effortless, whereby responsiveness and sensitivity are increased; also to provide an automatic safety arrangement to limit piston movement but at the same time to protect the operator from injury if the piston should overrun its stroke limit.

15 Essentially, the apparatus constitutes a fluid relay system interposed between the hand lever and main steam control valve, arranged to transmit the movements of the hand lever to the control valve in duplicate and almost instantly, by fluid pressure. In its preferred form, the apparatus is powered by hydraulic pressure for more positive operation, actuating force to move the main steam valve being developed by a hydraulic cylinder having a piston connected to the control rod of the steam valve. A plunger type hydraulic pilot valve is hydraulically connected to the cylinder, the pilot valve being arranged to lock the piston hydraulically in fixed position or 20 to move the piston in either direction depending upon pilot plunger movement. A control handle is connected to the pilot valve plunger and the pilot valve casing is connected to and movable with the piston of the hydraulic cylinder.

25 30 35 40 45 When the handle is moved in a given direction from neutral, the pilot valve plunger is moved from a neutral position to admit hydraulic pressure to an end of the cylinder to move the piston and steam valve in a corresponding direction. Since the pilot valve casing moves with the hydraulic piston and steam valve stem, it moves relative to its plunger to reestablish the neutral condition, thus hydraulically locking piston and steam valve in open position so long as the handle is held in that position. The steam reversing valve normally is maintained in a neutral closed position corresponding to the handle neutral position and when the handle thus is actuated, 50 the steam valve is opened to drive the steam

piston in a corresponding direction. In other words, the hydraulic piston and steam valve follow precisely the movements of the pilot valve plunger in either direction.

There is very little lag between the movements of the hydraulic valve plunger and operation of the hydraulic piston steam valve follows handle movements almost as if the handle were connected directly to the steam valve stem except that the effort to move the handle is eliminated. This leads to greater precision in controlling the extrusion operation as well as relieving the operator of physical strain.

A safety interlock is interconnected between the steam piston and hydraulic control apparatus to close the steam control valve before the piston contacts the top cylinder head. This device reverses the pilot valve so as to close the steam valve when the piston actuates the interlock near its retracting stroke limit. Since the operator is at this time holding the handle in piston retracting position, the safety apparatus is yieldably connected to the handle to absorb the impact and prevent kicking of the handle. However, a slight pressure impulse is transmitted to the handle to indicate to the operator that the limit of piston travel has been reached.

It is to be observed that the apparatus can be built readily into new machines instead of converting existing equipment to hydraulic relay operation as disclosed. From the following description with reference to the drawings showing the invention embodied in an extrusion machine, those skilled in the art will comprehend readily the various other uses to which the invention may be applied.

In the drawings:

Figure 1 is a fragmentary side elevation of a steam extrusion press equipped with the improved hydraulic control apparatus.

Figure 2 is a view of the structure as projected from Figure 1, further illustrating the complete structure.

Figure 3 is an enlarged fragmentary view of the hydraulic apparatus and control linkage as viewed in Figure 2, shown separated from the extrusion press.

Figure 4 is a fragmentary view projected from Figure 3, further illustrating the control apparatus.

Figure 5 is a fragmentary diagrammatic view illustrating the operation of the apparatus with the secondary control rod at its upper limit of travel.

Figure 6 is a fragmentary view similar to Figure 5, illustrating the operation of the safety interlock with respect to the pilot valve when the steam piston reaches its upper stroke limit.

Figure 7 is an enlarged fragmentary view taken on line 7-7, Figure 4, illustrating the yieldable connection between the actuating lever and secondary control rod.

Figure 8 is an enlarged fragmentary sectional view taken on line 8-8, Figure 1, illustrating the safety interlock connection and spring arrangement at the upper end of the steam valve stem.

Figure 9 is a diagrammatic view illustrating a reversible pilot valve and hydraulic cylinder hydraulically and mechanically interconnected to provide the hydraulic relay operation.

As disclosed in its preferred embodiment, the control apparatus is applied to a steam operated clay extrusion machine but it will be evident that it can be applied as well to various hydraulic or air operated machines. The press illustrated is

a conventional machine which is in extensive use in the clay pipe industry. The pipe lengths are extruded from clay and while still in plastic condition they are trimmed accurately to length, their ends are shaped according to type and other necessary operations are performed, after which the sections are baked and fired.

As disclosed in Figure 1, the machine rests upon a base or foundation formed from steel I-beams 10-10 which may be located at floor level. Rising from the foundation is a steam cylinder indicated generally at 11 and beneath the foundation there is secured an extrusion unit generally indicated at 12 through which the plastic clay is forced under pressure developed by the steam cylinder. The cylinder assembly 11 is supported upon vertical studs or tie bolts 13 rising from the foundation I-beams and secured to the lower cylinder head 14. The cylinder includes a top cylinder head 15 and a piston 16 having a piston rod passing through a packing gland 17 forming a part of the lower cylinder head 14. The lower end of the piston rod carries an extrusion ram 18 which traverses the extrusion chamber 20 to force the plastic clay under pressure through the extrusion die 21 at the lower end of the chamber. The extruder chamber is charged with the ram in an elevated position in which position the upper end of the extrusion chamber is exposed.

The piston and ram movements are controlled by the steam throttle valve 22 having neutral, forward and reverse positions to control the direction and rate of piston travel. This valve may follow any conventional design and for this reason is not disclosed in detail. It is to be noted that this valve in the past has been actuated manually by a control lever connected directly to the valve stem 24. The operation of the valve is regulated by vertical movements of the stem 24 and the valve is provided with a steam supply pipe 25, an exhaust pipe 26, and respective steam pipes 27 and 28 leading from the valve to the top and bottom of the cylinder assembly.

When the valve stem 24 is in neutral or intermediate position, the steam supply pipe 25 is blocked and piston 16 is stationary. When the stem is lowered, steam is passed from supply pipe 25, through the valve to pipe 21, into the upper end of the cylinder to force piston 16 downwardly while steam is exhausted from the lower end of the cylinder through pipe 28, through the valve to exhaust pipe 26. When the valve stem is raised above neutral position, the passage of steam is reversed to raise the piston. Rate of piston travel is controlled by the degree of stem movement which provides a throttling action. The steam press is provided with other structure suitable to guide and support the extruded clay tube lengths and to sever them but further disclosure is unnecessary to illustrate the salient features of the control apparatus.

Manual operation of the valve stem has been eliminated by the present hydraulic apparatus whereby the forces required to actuate the valve stem are developed by hydraulic pressure which in turn is controlled manually by a pilot valve, operable manually by the application of very slight force. As shown, the hydraulic apparatus in general constitutes a hydraulic cylinder and piston assembly 29 mounted upon the base 10 and having its piston rod 30 connected to the valve stem 24 by an intermediate rod 31. Application of hydraulic pressure to the top or bottom of the cylinder moves the steam valve stem to actuate the steam piston in the same direction.

Operation of the hydraulic cylinder is controlled by a hydraulic pilot valve, the casing 32 of which is mounted upon and movable with the steam valve rod 31. The pilot valve includes a valve plunger 33 operatively connected to a secondary manually actuated control rod 34 which is moved vertically by a control lever 35.

As hereinafter disclosed with reference to the hydraulic diagram of Figure 9, the hydraulic pilot valve acts as a reversing valve for which purpose it has a neutral, forward and reverse position, corresponding to the positions of steam valve 22, and is connected by the flexible conduits 36 and 37 to the top and bottom of the hydraulic cylinder. Pressure and exhaust conduits 38 and 39 connect the pilot valve with a hydraulic supply system (not shown) to supply hydraulic pressure to the cylinder 29 under control of the valve. The operation is such that the valve and its cylinder operate as a servo-motor interconnecting the secondary rod 34 with the steam valve stem 24. In other words, upward movement of the secondary control rod shifts the valve plunger 33 upwardly, which in turn conditions the valve to apply hydraulic pressure through conduit 31 to the bottom of hydraulic cylinder 29 to cause the valve stem to move upwardly. Upward movement of the valve stem carries with it the casing of the pilot valve until the valve regains its neutral condition at which point movement is halted.

The manual control lever 35 therefore may be swung in either direction and the valve thereupon is in condition to move the valve stem in the same direction and this follow-up movement will continue so long as the secondary control rod is in motion. The steam valve therefore will be shifted to supply steam to the cylinder in accordance with the direction of movement of the control lever 35 from its neutral position. As previously noted, the hydraulic cylinder assembly 29 is quickly responsive to pilot valve movements so that a very slight movement of the valve plunger 33 is reproduced almost instantly by the hydraulic piston and steam valve stem 24.

Described in detail, the hydraulic cylinder 29 is mounted upon a pair of channel members 40-40 extending crosswise of the I-beams 10-10 (Figure 3 and 4). A mounting plate 41 is secured upon the top of the channel irons and an I-bolt 42 is screwthreaded into the mounting plate. The hydraulic cylinder is connected to the I-bolt by means of a pair of spaced lugs 43 embracing the opposite sides of the I-bolt and connected to the bolt by a pivot pin 44. The application of hydraulic pressure to the top or bottom of the cylinder therefore will cause the valve stem to move in the appropriate direction. The pilot valve 32 is fixed upon the intermediate valve stem rod 31 by means of the lugs 45-45, forming a part of the valve casing and secured in fixed position upon the stem by means of set screws 46 threaded through the lugs and engaging the stem. The upper end of the rod 31 includes a knuckle joint formed by an I-bolt 47 connected to the valve stem 24 just below the steam valve. Incorporated in the knuckle joint is a drain guard 48 to collect leakage which may pass through the packing gland 50 of the valve. Valve stem 24 extends through the steam valve, passing through a packing gland 51 at the top of the valve.

The secondary control rod 34 constitutes a lower section 52 and an upper section 53, both of tubular construction and slidably connected

together by a stud 54 having its lower end secured rigidly in the lower rod section 52 and its upper end slidably disposed within the upper rod section 53 (Figure 3). The secondary rod is connected to the actuating lever 35 by means of a bellcrank lever 55 pivotally connected by a pivot pin 56 secured to the channel 57 which is mounted upon the bottom of the channels 40-40.

The bellcrank lever includes a detent sector 58 (Figure 4) having a V-shaped notch 60 in which is cradled a roller 61 mounted upon the swinging end of an arm 62 having its opposite end pivotally mounted in a bearing block 63 mounted upon channel 57. A spring 64 has its upper end hooked upon a pin 65 extending from arm 62 and its lower end anchored upon a bolt 66 mounted in the channel 57. This spring is maintained under tension to urge the roller 61 into engagement with the V-shaped notch 60 to maintain the control lever 35 and its linkage in a neutral position by virtue of the cam action of the roller with respect to the notch. Operation of the lever in either direction is resisted by the spring 64.

The secondary rod 34 is connected to the plunger 33 of the pilot valve by a lateral arm 67 secured upon the secondary rod section 52 and having its outer end pivotally connected as at 68 to an adjustable link 70, the upper end of which is pivotally connected as at 71 to the end of the valve plunger 33. It will be observed therefore that when the control lever is swung to the right as viewed in Figure 4, the secondary control rod and valve plunger will be elevated and when the lever is swung to the left the rod and stem will be lowered. When the lever is swung to elevate the valve plunger, the valve will supply hydraulic fluid to the lower end of the hydraulic cylinder 29 causing the piston rod 30 and valve stem 24 to rise, carrying with it the pilot valve casing relative to its plunger until the valve reaches a neutral position. The apparatus will remain in this position until the lever either is returned to neutral or advanced further; in either case the pilot valve casing will follow movements of the pilot plunger. In the position shown in Figure 4, the steam control valve 22 is in neutral position with the steam piston stationary and when the lever 35 is swung in either direction the steam valve will be conditioned to apply steam pressure for operation in the appropriate direction by operation of the hydraulic valve and cylinder.

In order to prevent the steam piston from rising beyond its upper stroke limit, there is provided an automatic linkage system which reverses the hydraulic pilot valve to close the steam valve as the piston approaches its upper limit. The linkage structure is best shown in Figures 1 and 8 and the operation is illustrated diagrammatically in Figures 5 and 6. For this purpose, there is provided a plunger 72 (Figure 1) passing through the top cylinder head 15 and slidably sealed with respect to the cylinder head by a packing gland 73. A lever 74, centrally pivoted as at 75, has one end in operating engagement with the plunger 72 and its opposite end pivotally connected as at 76 to a sleeve 77 slidably mounted upon the upper end of the valve stem 24. A spring 80 is mounted under compression between the top of the valve and a collar 82 forming a part of sleeve 77, the spring serving to maintain the sleeve and its associated linkage in an elevated position as shown. Fixed to the lower end of the sleeve is a lateral arm 83 to

which is pivotally connected as at 84 the upper section 53 of the secondary control rod 34. The lower end of this rod is telescopically engaged upon the end of the stud 54 previously described. There is provided also a slide bracket 85 secured to the pilot valve arranged to maintain the secondary rod section 53 in alignment with section 52.

When the steam piston 16 approaches its upper limit of travel, the collar 86 of stud 54 will be 10 closely adjacent the lower end of rod 53 as shown diagrammatically in Figure 5. When the piston contacts plunger 72 it will rock lever 14 in a direction to force sleeve 17 downwardly against the compression of spring 80. This motion will be transmitted to rod section 53 through the arm 83, causing rod section 53 to contact collar 86 to urge the lower rod section 52 downwardly thus 15 lowering the plunger 33 of the hydraulic control valve. Pilot valve operation will of course cause the valve stem 24 to be lowered, cutting off the flow of steam to the lower side of the cylinder and halting the piston travel in the same manner as if the control lever had been swung manually to neutral position.

In view of the fact that the control lever must be held manually to the right to elevate the rod section 52 and collar 86 to the position shown in Figure 5 during the rise of the piston, it will be apparent that the operator would be subjected to a shock when lever 74 is actuated by the steam piston at its upper limit of travel. In order to avoid this condition, the connection between the bellcrank lever and secondary control rod 52 is yieldable. This structure is detailed in Figure 7 and as disclosed, constitutes an I-bolt 87 pivotally connected as at 88 to the swinging end of bellcrank 55 and having its shank 89 slidably mounted in the lower end of the tubular control rod 52. A preloaded compression spring 90 is interposed between the upper end of the shank 91 and a cross pin 92, passing through the tubular rod, engages the upper end of the spring. The lower end of the control rod is slotted as at 93 and the I-bolt shank is secured against endwise displacement by a cross pin 94 passing through the shank and having its opposite ends engaged in the slot. Compression spring 90 is preloaded to the extent that under normal operation, the I-bolt 87 and secondary control rod section 52 move as a unit with the cross pin 94 engaged against the bottom of slot 93 as shown, the resistance of the hydraulic pilot valve being very slight. However, when the safety device goes into action, the rod section 52 is depressed against the spring 90 so that the motion is not transmitted to the control lever 35, thereby preventing the lever from being kicked and possibly injuring the operator.

As shown in Figure 5, the pilot valve plunger 33 and its control rod section 52 are elevated to the upper limit of travel by the hand lever 35. In order to clarify the operation, the direction of valve plunger movement is indicated by solid arrows and the pilot valve casing 32 and rod 31 of the control valve stem are shown in position prior to responsive movement, as indicated by broken arrows, although in practice the hydraulic cylinder 29 responds almost instantly so that the pilot valve casing maintains its relative position with the pilot plunger. As shown diagrammatically in Figure 6, the upper valve rod section 53 is shown depressed by the interlock linkage, the direction of movement also being shown by solid arrows. When this occurs, the hydrau-

lic cylinder and pilot valve casing respond immediately to pilot plunger movement but the diagram shows the pilot valve casing in its original position to illustrate the operation more clearly.

The direction of pilot valve casing and power valve stem movement is illustrated in broken arrows in the same manner as shown in Figure 5. It will be noted in this view that the spring 90 is depressed to permit the lower rod section to move relative to the bellcrank lever 55 of control lever 35 to permit the lever to remain stationary.

The hydraulic circuit, as illustrated diagrammatically in Figure 9, constitutes substantially a reversing system, the pilot valve 32 having a neutral or closed intermediate position and an elevating and lowering position to control the movements of the hydraulic cylinder. The pilot valve and cylinder preferably are commercial products and for this purpose are illustrated in diagrammatic fashion. As previously described, the valve embodies a casing 32 and a movable plunger 33, movable relative to the casing by the control lever 35. The casing is provided with pressure inlet ports 95 and 96 and an exhaust port 97, connected by the conduits 38 and 39 to a hydraulic supply system (not shown). The casing further is provided with fluid delivery ports 98 and 100 which are connected by the flexible conduits 36 and 37 respectively to the upper and lower ends of the hydraulic cylinder. The plunger is necked to provide the plunger ports 101 and 102. In the position shown, the valve is in a neutral position with the delivery ports 98 and 100 blocked by the valve plunger thus locking the piston of the hydraulic cylinder in fixed position.

When the control lever is shifted in a direction to elevate the valve plunger, delivery port 100 will be uncovered and hydraulic pressure will flow through port 95, through plunger port 102 to port 100 and through conduit 37 to the lower end of the hydraulic cylinder. This causes the valve casing to be elevated to reestablish the neutral condition of the valve, at which time the hydraulic piston will again be hydraulically locked. As fluid enters the lower portion of the hydraulic cylinder, it will be exhausted from the upper end through conduit 36, casing port 98, through plunger port 101 to conduit 39 back to the supply unit.

If the valve plunger is shifted downwardly, hydraulic pressure will be admitted through port 96, port 98, conduit 36 to the upper end of the hydraulic cylinder causing the hydraulic piston to move downwardly a corresponding distance to reestablish the neutral condition. If the control lever is held in piston elevating position until the safety device operates, the pilot plunger will be shifted downwardly by the lever 74 against compression of spring 80 as previously described, to reverse the pilot valve circuit to close the steam valve independently of the position of the hand lever.

Having described my invention, I claim:

1. An operating mechanism for shifting the longitudinally movable stem of a reversing steam valve through the medium of a hydraulic servomotor apparatus, the steam valve having an intermediate closed position, the servomotor apparatus having a hydraulic relay cylinder including a piston connected to the steam valve stem for moving the same in alternate directions from the intermediate position, a hydraulic pilot valve casing mounted on the steam valve stem, and a plunger within the pilot valve casing movable

relative to the casing; said operating mechanism comprising a longitudinally shiftable control rod mounted in parallelism with the steam valve stem, a member extending laterally from the control rod connected to said movable pilot valve plunger for shifting the same relative to the valve casing directly in unison with the longitudinal movements of the control rod, a hand lever mounted upon a pivot point adjacent an end of the control rod, said hand lever having a lever extended from the pivot point and connected to the end of the control rod for shifting the control rod and valve plunger upon swinging movement of the hand lever, and yieldable means adapted to maintain the hand lever normally in an intermediate position, the pilot valve constituting a reversing valve having hydraulic pressure supply and exhaust conduits connected to a source of hydraulic pressure and having flexible conduits extending from the casing to the opposite ends of the hydraulic relay cylinder arranged to supply hydraulic fluid to the opposite ends of the cylinder upon longitudinal movement of the pilot valve plunger relative to the valve casing, the valve plunger having an intermediate closed position for blocking the said flexible conduits whereby the hydraulic relay cylinder and steam valve stem are locked hydraulically in fixed position when the control lever is released and swung to said intermediate position by said yieldable means, the hydraulic pilot valve being operable to shift the steam valve stem in alternate directions from the intermediate position in response to swinging movements of the control lever in either direction from said intermediate position.

2. An operating mechanism for shifting the longitudinally movable stem of a reversing steam valve through the medium of a hydraulic servo-motor apparatus, the steam valve having an intermediate closed position, the servo-motor apparatus having a hydraulic relay cylinder including a piston connected to the steam valve stem for moving the same in alternate directions from the intermediate position, a hydraulic pilot valve casing mounted on the steam valve stem, and a plunger within the pilot valve casing movable relative to the casing; said operating mechanism comprising a longitudinally shiftable control rod mounted in parallelism with the steam valve stem, a member extending laterally from the control rod connected to said movable pilot valve plunger for shifting the same relative to the valve casing directly in unison with the longitudinal movements of the control rod, a hand lever mounted upon a pivot point adjacent an end of the control rod, said hand lever having a lever extended from the pivot point and connected to the end of the control rod for shifting the control rod and valve plunger upon swinging movement of the hand lever, and a detent device adapted to maintain the hand lever normally in an intermediate position, the detent device having a sector mounted upon the hand lever for swinging movement in unison therewith, the sector including a detent notch, a yieldable detent member in pressure engagement with said notch adapted to urge the detent sector and hand lever normally to said intermediate position, the pilot valve constituting a reversing valve having hydraulic supply and exhaust conduits connected to a source of hydraulic pressure and having flexible conduits extending from the casing to the opposite ends of the hydraulic relay cylinder arranged to supply hydraulic fluid to the opposite

ends of the cylinder upon longitudinal movement of the pilot valve plunger relative to the valve casing, the valve plunger having an intermediate closed position for blocking the said flexible conduits whereby the hydraulic relay cylinder and steam valve stem are locked hydraulically in fixed position when the control lever is released and swung to said intermediate position by said detent device, the hydraulic pilot valve being operable to shift the steam valve stem in alternate directions from the intermediate position in response to swinging movements of the control lever in either direction from said intermediate position.

3. An operating mechanism for controlling the piston of a steam cylinder through the medium of a hydraulic servo-motor apparatus, the steam cylinder being controlled by a reversible steam valve having a longitudinally movable stem, said servo-motor apparatus having a hydraulic relay cylinder including a piston connected to the steam valve stem for moving the stem, a hydraulic pilot valve casing mounted on the steam valve stem, and a pilot valve plunger mounted for relative movement within the casing, said pilot valve casing being hydraulically connected to the relay cylinder and being adapted to shift the relay piston from a neutral position in response to a corresponding movement of the pilot valve plunger; said operating mechanism comprising a longitudinally movable sectional control rod, a pivotally mounted hand lever having a lever extension pivotally connected to one section of said control rod for manually shifting the same longitudinally, means connecting the pilot valve plunger to said control rod section for movement of the valve plunger directly in unison with the longitudinal movements of said control rod section, the control rod having a second section including an end telescopically engaged upon the first section and adapted to be moved longitudinally relative to the first section, an interlock lever pivotally mounted upon the steam cylinder, means connecting an end of said interlock lever to the second control rod section, a push rod slidably mounted in said steam cylinder and connected to the opposite end of said interlock lever, said push rod adapted to be engaged and shifted by the steam piston when the piston reaches a predetermined stroke limit, stop means on the first control rod section engageable by the telescopically engaged end of the second control rod section upon longitudinal movement thereof by said interlock lever whereby the second control rod section is operable to move said first control rod section and shift the pilot valve plunger to neutral position.

4. An operating mechanism for controlling the piston of a steam cylinder through the medium of a hydraulic servo-motor apparatus, the steam cylinder being controlled by a reversible steam valve having a longitudinally movable stem, said servomotor apparatus having a hydraulic relay cylinder including a piston connected to the steam valve stem for moving the stem, a hydraulic pilot valve casing mounted on the steam valve stem, and a pilot valve plunger mounted for relative movement within the casing, said pilot valve casing being hydraulically connected to the relay cylinder and being adapted to shift the relay piston from a neutral position in response to a corresponding movement of the pilot valve plunger; said operating mechanism comprising a sectional control rod, a pivotally mounted hand lever having a lever extension pivotally connected

to one section of said control rod for manually shifting the same longitudinally, means connecting the pilot valve plunger to said control rod section for movement of the valve plunger in unison with the longitudinal movements of said control rod section, a compression spring interposed between the lever extension and said control rod section, said compression spring providing longitudinal movement of the control rod section and valve plunger relative to the lever extension in a direction to shift the valve plunger to said neutral position, the control rod having a second section including an end telescopically engaged upon the first section and adapted to be moved longitudinally relative to the first section, an interlock lever pivotally mounted upon the steam cylinder, pivot means connecting an end of said interlock lever to the second control rod section, a push rod slidably mounted in said steam cylinder and connected to the opposite end of said interlock lever, said push rod adapted to be engaged and shifted by the steam piston when the piston reaches a predetermined stroke limit, stop means on the first control rod section engageable by the telescopically engaged end of the second control rod section, said stop means being spaced from said engaged end adapting the first rod section to be shifted longitudinally relative to the second rod section in response to hand lever movements, said stop means being engaged by the second rod section upon shifting of the interlock lever, whereby the second rod section is effective to move the first rod section counter to said compression spring and thereby shift the pilot valve plunger to neutral position.

5. An operating mechanism for controlling the piston of a vertical steam cylinder through the medium of a hydraulic servo-motor apparatus, the steam cylinder having a reversible steam valve including a longitudinally movable stem extending vertically therethrough, said servo-motor apparatus having a relay cylinder including a piston connected to the steam valve stem for moving the same, a pilot valve casing mounted on the steam valve stem, and a pilot valve plunger in said casing movable relative to the casing, the valve casing being hydraulically connected to the relay cylinder and adapted to shift the relay pis-

ton from a neutral position in response to a corresponding movement of the pilot valve piston; said operating mechanism comprising a longitudinally shiftable control rod mounted vertically in parallelism with the steam valve stem, a lateral member connecting the control rod to the pilot valve plunger for moving the plunger in unison with the control rod, a hand lever pivotally mounted adjacent the lower end of the control rod and connected thereto, the hand lever being adapted to shift the control rod and pilot valve plunger upon movement of the hand lever, a yieldable member interposed between the hand lever and control rod adapted to yield when the control rod is forced downwardly toward the hand lever, a second control rod telescopically engaged upon the upper end of the first mentioned control rod, a sleeve slidably mounted upon the steam valve stem above the valve, a compression spring interposed between the sleeve and valve adapted to urge the sleeve upwardly, a lateral member connecting the sleeve to the second control rod, an interlock lever pivotally mounted above the steam cylinder having an end connected to the sleeve, means on the opposite end of the interlock lever for shifting the same in response to movement of the steam piston to its stroke limit whereby the sleeve is shifted downwardly, and stop means on the first mentioned control rod adapted to be engaged by the second control rod section upon downward movement thereof by said interlock lever whereby the interlock lever is effective to shift the control rod and pilot valve plunger to a neutral position independently of the position of the hand lever.

CECIL E. WEBB.
